RAILWAY DUMP CAR

Carl P. Astrom, East Orange, N. J., assignor to
 M. H. Treadwell Company, Inc., New York,
 N. Y., a corporation of New York

Application August 8, 1942, Serial No. 454,117

7 Claims. (Cl. 105—267)

The invention relates to railway cars having tilting containers, such as twin pot cinder cars and the like, and more particularly to latching mechanism for holding the containers against tilting, and for releasing them for tilting.

In my prior Patent No. 1,613,153, and in my copending application, Serial No. 454,116, filed August 8, 1942, there are shown dumping cars having tilting containers of a type to which my present invention is applicable. It is one of the objects of my invention to provide an improved tilting container car of this type and, more particularly, one which has a latching mechanism for the containers that is simple in construction and easy to operate under load.

Tilting container cars used in steel plants for handling molten slag and cinder from furnace to dump consist of a railway car underframe on which are carried ladies or pots slung in bails, the bails having power driven means arranged to tilt the pots to one side of the car or the other as may be desired. The pots, or the bails which carry them, have trunnions which support them on suitable frames for tilting movement about the trunnion axis. Normally the pots are held in a vertical position. When the center of gravity of the loaded pot is above the horizontal plane of the trunnion axis, there exists a torque producing a turning moment on the pot about this axis, the direction of which depends on whether the center of gravity is to one side or the other of the vertical plane of the axis. This turning moment is resisted by the mechanism used for tilting the ladle or by the safety latch, or both. When it is resisted by the safety latch, the operation of the latch becomes difficult, and the jamming action of the pot, or its supporting bail, against the latch at times may be such as to make it impossible to release the latch for dumping the pot. It is also possible for the pot to become jammed between the opposing forces or reactions of the operating mechanism and the latch, in which case a similar difficulty will be encountered when it is attempted to release the latch. It is an object of my invention to provide latching means for cars of the class described which overcomes the operating difficulties encountered under any of the conditions above described.

Another object of the invention is to provide latching mechanism of the class described which is adapted for two-way operation, that is, for releasing the container for tilting in either direction; also, which operates effectively under initial turning moments tending to tilt the con-

tainer either in the desired direction or in a direction opposed thereto.

Another object is to provide latching mechanism having reversible parts so that it can be arranged for operation from either side of the car; also, which is operable from a position in which the operator is safely removed from the tilting container.

Other objects and advantages of the invention will appear as the description proceeds.

In the drawings, which illustrate the application of my invention to a twin pot cinder car, Fig. 1 is a side elevational view of the car, and Fig. 2 an end elevational view thereof, showing the mechanism for tilting the pots.

Fig. 3 is a detail sectional view taken on the line 3—3 of Fig. 2.

Figs. 4, 5 and 6 are detail views of the latching mechanism, Fig. 4 being a transverse sectional view taken as indicated at 4—4 in Fig. 1, and Figs. 5 and 6 being a top view and side elevational view, respectively, of the operating handle. (Fig. 5 is taken as indicated at 5—5 in Fig. 4.)

The railway car which has been selected for the purpose of illustrating a specific embodiment of the invention consists, in its general arrangement, of an underframe 1 carried by trucks 2 of any suitable construction well known in the art, tilting containers or pots 3 resting in bails 4 provided with trunnions 5 by which the containers are supported on tracks 6 extending transversely of the car and mounted on suitable supporting framework 7, 8, 9, and power driven operating means 10 for tilting the containers and moving them laterally of the car by rolling the trunnions 5 along the tracks 6. The bails 4 are joined by a universal coupling 11 so that the operating mechanism 10 actuates both of the containers 3.

In their limiting position, the containers 3 engage the underframe of the car or stop members 12 thereon. If desired, the containers may be provided with stops or bumpers 13 for engagement with the aforesaid stop members 12 on the underframe.

Referring to Figs. 2 and 3, the power driven operating means indicated generally at 10 comprises a driven screw member 14 and cooperating nut 15 secured to a bearing member 19 rotatably mounted in the trunnion 5 of the bail 4. A gear sector 16 is keyed to the trunnion 5 and is arranged for engagement with a transversely extending rack 17 mounted on the frame member 9. If desired, the rack 17 may be formed integrally with the track 6.

In the preferred construction illustrated, the bail trunnion 5 adjacent the operating means is apertured at 18 to receive the bearing member 19, the bearing surfaces 20 and 21 of which are carried in cylindrical bushings 22 and 23 pressed into counterbores aligned with the aforesaid aperture 18 in the trunnion 5 of the bail 4. The trunnion 5 may be provided with a flange 24 for engagement with the inside of the track 6. The nut 15 is provided with a pair of apertures 25 to receive the bifurcated ends 26 of the bearing member 19. Pins 27 passing through apertures in the nut 15 and bifurcated ends 26 of the bearing member secure the nut and bearing member together.

The track 6 adjacent the rack 17 is provided with upwardly curving ends 28 which limit movement of the trunnion 5 transversely of the car. A complementary upper track member 29 with downwardly curving ends 30 secured to the upwardly curving ends 28 of the track 6 engages the upper side of the trunnion 5. Normally, the gear 16 is held in engagement with the rack 17 by the weight of the container 3 (and its contents). However, the provision of the upper track member 29 insures that the gear and rack will be held in proper engagement under all conditions of operation. A flange 31 strengthens the rack 29 against bending.

Any suitable drive means may be provided for the screw member 14. In the construction shown, a motor 32 mounted on the underframe in any convenient manner has a pinion 33 meshing with a gear 34 keyed to a shaft 35 journaled in bearings on the frame 9 to the other end of which shaft is fixed a pinion 36 meshing with a gear 37 keyed to a shaft 37' in line with the screw 14 and connected thereto through a universal joint 38.

In accordance with my invention, the containers are locked in their vertical position not only by the screw 14, but also by the latch mechanism which will now be described with particular reference to Figs. 4, 5 and 6 of the drawings. The latch mechanism comprises, in its general arrangement, a latch or pair of latches 40 arranged for engagement with the tilting container, or with a member which is fixed with respect to the container, such as the bail 5 or lugs 41 fixed thereto, an operating member for the latches such as the handle 42, the latches and handle being resiliently connected through an eccentric cam 43 and a pair of telescoping link members 44, 45 having spring means or other resilient means which permit selective setting of the handle 42 for open or closed position of the latches prior to actual release or locking thereof so that the latch will be self-actuated upon tilting of the container. There are thus provided latch means for holding the container against tilting, means for resiliently applying a force to the latch (or latches) tending to release it while it is restrained by the container against actual release.

In the specific embodiment illustrated, the bail 4 of one of the containers 3 is provided adjacent one of its trunnions 5 with a downwardly extending flange 46 on which are formed the aforesaid lugs 41. The flange 46 may conveniently be formed as an extension of the flange 24 of the trunnion 5 as best shown in Figs. 3 and 4. The latches 40 are pivotally mounted on the frame 9, as by means of bolts 47. Each latch is provided with an arm or pair of arms 48 to one of which is pivotally secured the aforesaid link member 45. In the construction shown, the upper arm 48 of the left-hand link 40 (Fig. 4) is connected to the

lower arm 48 of the right-hand latch by a pair of links 49 or by a link having bifurcated ends, as may be desired. The link 45 is in the form of a tubular member (Fig. 6) provided with a bifurcated end 50 arranged to receive the links 49 which, together with the bifurcated end 50 and arm 48, are apertured to receive a connecting pin 51. A connecting pin 52 pivotally secures the other ends of the links 49 to the upper arm 48 of the other latch.

In my preferred construction, the operating member 42 comprises a rod or shaft 53 (Figs. 1 and 5) journaled in the frame 9, the shaft 53 being of considerable length so that the handle 15 42 is located at the end of the car in a position in which the operator is safely removed from the tilting containers. Keyed to the other end of the shaft 53, as at 54, is the eccentric cam 43 previously referred to, engaged by a strap 56 fixed to the aforesaid link member 44. Annular plates 57 overlying the strap 56 and a portion of the eccentric cam 43 may be riveted or otherwise secured to the strap 56, as at 58, to hold the eccentric and strap in operating engagement.

Link member 45, which, as previously stated, is of tubular form, is provided with a circumferential shoulder 59 dividing its interior into two compartments with an opening 55 therebetween. Link member 44 extends through the end of the member 45 and the opening 55. Compression springs 60 and 61 surround the link member 44 and are disposed in the respective chambers of the member 45. The spring 60 bears at one end against the shoulder 59, and at the other end against a nut and lock nut 62. Spring 61 bears at one end against the shoulder 59, and at the other end against a collar 63 secured to the member 44. The springs 60 and 61 are arranged to resist lengthening and shortening of the resilient connection provided by the telescoping or slidably-arranged link members 44, 45.

When the tilting containers are locked in their normal upright positions, as when the car is in motion, the handle 42 occupies the position shown in the Figs. 4, 5 and 6. When it is desired to tilt the containers for unloading, the handle is moved in the direction of the arrow *a* (Fig. 6) until it reaches a position 180° from the position illustrated. If the latches 40 are free, they will be moved into position to release the containers for tilting. Under any of the conditions previously described, which result in restraining of the latches by reason of the jamming action of the pot, or its supporting bail, against one of the latches, the latches remain in the position shown in Fig. 4 during movement of the handle through 180° from the position illustrated. This action results in compression of the spring 61. The motor 32 then is started in a direction to produce tilting of the container in the direction which will release the latch that is jammed. At the moment of such release, the spring 61 extends, pushing the link member 45 to the left and releasing both of the latches. The initial movement of the containers to free the latches may be in the desired direction of tilting, or may be in the opposite direction. If the latter, the motor 32 is reversed at the moment that the latches are released. It will be understood from the preceding description that I have provided means for setting the latches when they are restrained by the container, for automatic release of the latches when the restraint is removed by operation of the container-actuating means.

At any time after the containers have been

tilted beyond the point of engagement of the latches with the lugs 41 on the bail, the latch operating handle 42 may be returned to the locked position shown in the drawings. This moves the latches into the position shown in Fig. 4 and compresses the spring 60 to a certain extent. Thereafter, when the containers are moved back into vertical position, the inclined surface 64 of one of the lugs 41 engages the inclined surface 65 of the corresponding latch member, further compressing the spring 60, which permits the latch to snap over the lug 41 to lock the container in vertical position.

A bracket 66 secured to the frame 9 is provided with flanges 67, 68 serving as stops to limit movement of the handle 42 in its open and closed (unlocking and locking) positions. These stops are so arranged as to arrest movement of the handle at points which bring it substantially in line with the links 44, 45 so that the eccentric cam 43 will be brought to a position at, or slightly beyond, dead-center. Thus, the handle locks at either end of its movement.

From the description which has preceded, it will be understood that I have provided means for selectively setting the latch for open or closed position prior to actual release or locking thereof, so that the latch will be self-actuated upon tilting of the container.

In my preferred construction, there is provided a bracket 69 corresponding to the bracket 66 at the other side of the car. This permits arrangement of the operating handle 42 on the other side of the car, in view of the provision of the second pair of arms 48 on the latches. The connection of the links 49 to the arms 48 may be reversed so that the latch-operating linkage is arranged on the axis shown by the broken line *b* in Fig. 4. In the operation of tilting the containers from the position shown in full lines at 3 (Fig. 2) to the position shown in broken lines at 3'—assuming that the latches have been released in the manner previously described—the motor 32 is operated in a direction to produce clockwise rotation of gear 37 as viewed in Fig. 1. This pulls the nut 15 to the right as viewed in Fig. 2, rotating the bail 4 and at the same time moving it laterally as the gear moves along the rack 17. Rotation of the bail 4 of the container adjacent the operating mechanism also serves to rotate bail 4 of the other container through the universal joint 11 (Fig. 1). The gear 16 at the opposite end of the car likewise travels over the rack 17 under this rotative action, producing uniform tilting of both containers.

The operation of the car for tilting containers 3 in the opposite direction from that shown at 3' in Fig. 2 is the same as described above, except that the motor is reversed.

The invention may be utilized in conjunction with tilting container cars of other constructions than that which I have specifically shown and described, and in conjunction with power operating means of other forms. It will be understood that it is applicable to cars having any desired number of tilting containers, or to a car having a single tilting container. The terms and expressions which I have employed are used in a descriptive and not a limiting sense, and I have no intention of excluding such equivalents of the

invention described, or of portions thereof, as fall within the purview of the claims.

I claim:

- 5 1. In a railway car having a tilting container, a latch arranged for engagement with a member fixed with respect to the container for holding the container against tilting, and an operating member for the latch, the operating member being spring-connected to the latch and arranged so that the operating member is selectively movable into latch-opening or latch-closing position by stressing of the spring connection prior to actual release or locking of the tilting container by the latch so that the latch will be self-actuated upon rocking of the container to and from its normal upright position.
- 10 2. In a latch mechanism for tilting dump car containers, a latch arranged for engagement with a member fixed with respect to the container, and an operating handle for the latch, the operating handle being spring-connected to the latch and movable into latch unlocking position by stressing of the spring connection when the latch is restrained in locking position by said first-named member.
- 15 3. In a latch mechanism for tilting dump car containers, a latch arranged for engagement with a member fixed with respect to the container, and an operating handle for the latch, the operating handle being resiliently connected to the latch through an eccentric cam and movable into unlocking position by stressing of the resilient connection when the latch is restrained in locking position by said first-named member.
- 20 4. In a latch mechanism for tilting dump car containers, a latch arranged for engagement with a member fixed with respect to the container, and an operating handle for the latch, the operating handle being resiliently connected to the latch through telescoping members having a spring resisting lengthening of said resilient connection.
- 25 5. In a latch mechanism for tilting dump car containers, a latch arranged for engagement with a member fixed with respect to the container, and an operating handle for the latch, the operating handle being resiliently connected to the latch through telescoping members having springs resisting lengthening and shortening of said resilient connection.
- 30 6. In a latch mechanism for tilting dump car containers, a latch arranged for engagement with a member fixed with respect to the container, and an operating handle for the latch, the operating handle being resiliently connected to the latch through an eccentric cam and a link comprising two members movable longitudinally relative to one another and springs resisting said longitudinal movement.
- 35 7. In a latch mechanism for tilting dump car containers, a latch arranged for engagement with a member fixed with respect to the container, an operating handle for the latch, a pair of telescoping link members one of which is connected to the latch and the other of which is connected operatively to the handle, one of said link members slidably arranged within the other, and spring means resisting said slidable movement.
- 40 8. In a latch mechanism for tilting dump car containers, a latch arranged for engagement with a member fixed with respect to the container, an operating handle for the latch, a pair of telescoping link members one of which is connected to the latch and the other of which is connected operatively to the handle, one of said link members slidably arranged within the other, and spring means resisting said slidable movement.
- 45 9. In a latch mechanism for tilting dump car containers, a latch arranged for engagement with a member fixed with respect to the container, an operating handle for the latch, a pair of telescoping link members one of which is connected to the latch and the other of which is connected operatively to the handle, one of said link members slidably arranged within the other, and spring means resisting said slidable movement.
- 50 10. In a latch mechanism for tilting dump car containers, a latch arranged for engagement with a member fixed with respect to the container, an operating handle for the latch, a pair of telescoping link members one of which is connected to the latch and the other of which is connected operatively to the handle, one of said link members slidably arranged within the other, and spring means resisting said slidable movement.
- 55 11. In a latch mechanism for tilting dump car containers, a latch arranged for engagement with a member fixed with respect to the container, an operating handle for the latch, a pair of telescoping link members one of which is connected to the latch and the other of which is connected operatively to the handle, one of said link members slidably arranged within the other, and spring means resisting said slidable movement.
- 60 12. In a latch mechanism for tilting dump car containers, a latch arranged for engagement with a member fixed with respect to the container, an operating handle for the latch, a pair of telescoping link members one of which is connected to the latch and the other of which is connected operatively to the handle, one of said link members slidably arranged within the other, and spring means resisting said slidable movement.
- 65 13. In a latch mechanism for tilting dump car containers, a latch arranged for engagement with a member fixed with respect to the container, an operating handle for the latch, a pair of telescoping link members one of which is connected to the latch and the other of which is connected operatively to the handle, one of said link members slidably arranged within the other, and spring means resisting said slidable movement.
